UNITED STATES PATENT OFFICE.

CHARLES W. PRICE, OF SPIRIT LAKE, IOWA.

SKATE-SHARPENER.

SPECIFICATION forming part of Letters Patent No. 750,696, dated January 26, 1904.

Application filed April 29, 1903. Serial No. 154,882. (No model.)

To all whom it may concern:

Be it known that I, CHARLES W. PRICE, a citizen of the United States, residing at Spirit Lake, in the county of Dickinson and State of Iowa, have invented a new and useful Skate-Sharpener, of which the following is a specification.

This invention relates to skate-sharpener; and one of the objects thereof is to provide means whereby a single holder can be employed to sharpen skates in all the different styles now generally employed.

A further object is to provide means for removably securing the cutting member within the holder.

A further object is to provide the holder of such construction that the cutting members will be interchangeable and easily applied.

Further objects and advantages of this invention will appear in the following description, and the novel features thereof will be particularly pointed out in the appended claims, it being understood that various changes in the form and the minor details of construction may be resorted to without departing from the spirit or sacrificing any of the advantages of this invention.

In the drawings, Figure 1 is a perspective view of a sharpener constructed in accordance with the invention. Fig. 2 is a longitudinal section of the same. Fig. 3 is a transverse section. Figs. 4, 5, and 6 are transverse sections, respectively, showing the modified cross-sectional constructions of cutting-tools.

As illustrated, the holder comprises two members 1 and 2, of approximately concave-convex formation and having parallel guide-flanges 3 and 4, between which the skate-runner will be guided into contact with the cutting-tool 5. The guide-flanges 3 and 4 are capable of receiving runners of varying widths or thicknesses, so that the groove to be cut will be perfectly straight. In order to hold the two members in proper rigid adjustment, I provide adjusting instrumentalities (illustrated as screws 6 and 7) which pass transversely through the sides of the two members, only one of which is engaged by the threads 8.

By simply turning the screws through the

medium of the heads 9 any distance may be 50 caused to intervene between the guide-flanges within the limits of adjustment of the screws.

Seats 10 and 11 are formed in the concave portions of the members 1 and 2 adjacent to the guide-flanges 3 and 4 for the reception of 55 the cutting-tool 5. This tool is designed to firmly engage the seats and is held in its seated position by clamping devices comprising screws 12 and 13, carried by the longitudinally-disposed block 14, loosely supported by 60 the adjusting devices 6 and 7. By loosely mounting the block 14 upon the adjusting devices 6 and 7 the members 1 and 2 can be adjusted to accommodate articles of varying 65 thicknesses, while permitting the block to remain in the longitudinal center of the intervening space between the guide-flanges 3 and 4, so as to exert a perfect clamping effect upon the cutting-tool 5.

In actual practice the screws 12 and 13 will 70 project through the intervening space between the opposing edges of the members 1 and 2 for convenience in manipulation, and by simply turning the screws so as to retract them from engagement with the cutting device 75 said cutting device can be removed and another one substituted.

In the several figures I have illustrated various forms of cutting devices or tools which appear to be best adapted to sharpen the skate-runner in the various styles now generally in vogue. However, I reserve the right to use any type of cutting-tool which will perform the necessary function of a device of this character.

I claim—

1. A skate-sharpener comprising two members, transverse adjusting means for the members, a separate block transversely adjustable on the adjusting means, and clamping means 90 carried by the block and projecting outwardly from between the two members.

2. A skate-sharpener comprising two members having depending guide-flanges, separate transversely-disposed devices for varying the 95 distance between the members, clamping devices, a block carrying the clamping devices and adjustable on the transversely-disposed

devices so that the clamping devices will at all times aline with the space between the two members.

3. A skate-sharpener comprising two members, a separate block, clamping means carried by the block and means for adjusting the two members and for moving the block so that the clamping devices will at all times aline with the space between the two members.
4. A skate-sharpener, comprising two relatively adjustable file-carrying members, a block movable separately of the members and

means for maintaining the block in constant alinement with the space between the adjustable members, and file-clamping means carried by the block.

In testimony that I claim the foregoing as my own I have hereto affixed my signature in the presence of two witnesses.

CHARLES W. PRICE.
